UNITED STATES PATENT OFFICE.

ALFRED N. OLSEN, OF ROCK RAPIDS, IOWA, ASSIGNOR OF ONE-HALF TO SAMUEL D. RINKER, OF ROCK RAPIDS, IOWA.

BOAT-PROPELLING POLE.

1,383,559.

Specification of Letters Patent. Patented July 5, 1921.

Application filed February 12, 1921. Serial No. 444,506.

To all whom it may concern:

Be it known that I, ALFRED N. OLSEN, a citizen of the United States, residing at Rock Rapids, in the county of Lyon and State of Iowa, have invented certain new and useful Improvements in Boat-Propelling Poles, of which the following is a specification.

The primary object of this invention is to provide means for propelling a boat through shallow water which, when in use, will obtain a firm footing against the muddy bottom so that a forward impulse may be imparted to the boat and which may be readily withdrawn from the mud without sticking therein. A further object of the invention is to provide a device for the stated purpose which may be stored within a small compass when not in use and which, when desired, may be employed as an ordinary paddle or oar. These stated objects and such other objects as will incidentally appear in the course of the following description are attained in such a device as is illustrated in the accompanying drawings and the invention resides in certain novel features which will be particularly pointed out in the claims following the description.

In the drawings

30 Figure 1 is an elevation of an implement embodying my invention;

Fig. 2 is an enlarged elevation of one end of the implement showing the working position of the mud-engaging member in full lines and showing by dotted lines the position assumed when the member is being withdrawn from the mud;

Fig. 3 is an enlarged bottom plan view of the parts shown in Fig. 2;

40 Fig. 4 is an enlarged longitudinal section showing the joint employed in the sectional handle.

In carrying out my invention, I employ a handle or pole consisting of similar sections 1 which may be provided in any desired number, three being shown in the accompanying drawings. One of these handle sections is provided with a paddle or oar blade 2, while the intermediate section is merely a coupling section for connecting the end sections, the end section remote from that carrying the blade 2 being equipped with a mud-engaging foot or presser plate 3. The sections of the handle or pole are detachably connected by the arrangement illus-

trated more particularly in Fig. 4. Secured to the end of one section is a coupling tube or sleeve 4 having annular spiral corrugations or threads 5 throughout its length from a point immediately adjacent the end of the section to the open end of the coupling sleeve. To the meeting end of the adjacent section, I secure a mating coupling sleeve 6 which is of less diameter than the first-mentioned coupling sleeve 4 so that it may fit within the said sleeve and this second coupling sleeve is provided with external beads or corrugations or threads 7 which are adapted to engage the corrugations, beads, or threads of the outer sleeve. It will be readily understood that the two handle sections may thus be easily connected when the device is to be used and may be as easily separated when it is desired to store or transport the device. The inner coupling sleeve 6 may be filled by the reduced end of the handle section to which it is secured or it may be otherwise reinforced against collapse so that lateral pressure exerted upon the handle at the joint will not bend or otherwise damage the same.

The pusher plate or foot 3 is preferably a substantial disk of metal to one side of which is secured a hinge leaf or plate 8 which hinge leaf or plate projects beyond the edge of the disk and has its projecting end formed into hinge eyes 9 which mate with the hinge eyes 10 at the end of a hinge leaf or member 11 which is carried by the adjacent handle section 1, a pintle 12 being inserted through the several hinge eyes so that the plate will be connected with the hinge, as shown. The hinge leaf 11 is preferably secured to a carrying plate 13 which in turn is secured rigidly to the adjacent handle section and has its free end formed into a hook 14 which partly encircles the hinge and has its extremity 15 arranged in the path of movement of the pusher plate or foot 3 so that the swinging movement of the plate will be limited, as will be readily understood upon reference to the dotted lines in Fig. 2. To the adjacent handle section 1, diametrically opposite the plate 13 and the hinge leaf 11, I secure a stop plate or tongue 16 which projects beyond the end of the handle section and is adapted at its free end to abut the foot or presser plate 3, as shown in Fig. 1 and by the full lines in Fig. 2.

It is thought the manner of using the device will be readily understood from the foregoing description, taken in connection with the accompanying drawings. When the boat is in shallow water so that a paddle or oar cannot be conveniently used, the pole is lowered in the water with the presser plate or foot 3 in the position shown in full lines in Fig. 2, so that the said plate or foot 10 will present a broad surface to the mud bottom and pressure applied upon the pole will effect propulsion of the boat. When the progress of the boat necessitates the removal of the pole, a pull is exerted thereon and the plate will readily leave the water if the bottom with which it is in contact happens to be moderately firm. If, however, the bottom is soft so that the presser plate or foot 15 tends to become embedded therein, the suction or hold of the mud upon the plate will cause it to swing to the position shown in dotted lines in Fig. 2 and present its edge to the line of movement of the pole so that the continued pull upon the pole will then 20 easily withdraw the plate or foot from the bottom. The edge or shoulder 15 presented to the plate 13 limits the movement of the foot or presser plate away from the stop bar 16 so that the foot cannot easily become 25 detached and lost and the said stop bar 16 by its abutting engagement with the plate or foot effectually prevents the foot folding against the end of the handle and holds it in such position that its entire area will be 30 presented to the water bottom and a sufficiently firm footing obtained to effect movement of the boat by the pressure exerted upon the pole. The device may be made in any desired size and may be readily dis- 35 jointed and stored in a small space when not in use. Of course, the paddle or oar 40 may be removed when the device is to be used as a push pole and the section carrying the presser plate or foot may be removed 45 when the device is to be used as an oar or a paddle, but such separation of the parts is not necessary and it may be desirable or 50 convenient to maintain the several sections of the handle in coupled relation. I prefer to locate one joint close to the paddle or

blade so that, with the blade removed, a long pole for pushing will be available.

The device is especially convenient for canoeists, hunters, or other persons using boats or canoes in very shallow water. In 55 navigating in very shallow water, it is frequently impossible to use the oar or paddle successfully and recourse is had to a pole for the purpose of pushing the boat off the muddy bottom and until deeper water is 60 reached. With an ordinary pole the end of the pole frequently becomes so embedded in the mud that the effort to extract the pole neutralizes the progress which was 65 made in propelling the boat, and when the bottom is very soft it is frequently impossible to find a sufficiently firm footing for the pole to obtain any benefit from the efforts to propel the boat. All these disadvantages 70 are overcome by the use of my device which is obviously simple in construction and may be produced at a very low cost.

Having thus described the invention, what is claimed as new is:

1. A device for the purpose set forth comprising a pole, a plate secured to and projecting from the end of the pole, a foot hinged to said plate, said plate being provided with a stop outwardly beyond the hinged connection of the foot to the plate 75 to limit the movement of the foot away from the pole, and an abutment projecting from the end of the pole and spaced from the plate to be engaged by the foot and limit the movement thereof toward the pole. 80

2. A device for the purpose set forth comprising a pole, a carrying member secured to and projecting from the end of the pole, a foot hinged to said carrying member, the end of said carrying member partly 85 encircling the hinged connection of the foot and presenting a stop thereto to limit the movement of the same away from the pole, and an abutment bar secured to the pole at a point remote from the carrying plate and 90 projecting beyond the end of the pole to be engaged by the foot and limit the movement of the same toward the pole. 95

In testimony whereof I affix my signature.
ALFRED N. OLSEN. [L.S.]
